UNITED STATES PATENT OFFICE.

THOMAS ALEXANDER SHEA, OF OSWEGO, NEW YORK, ASSIGNOR TO GEORGE B. SLOAN, JR., OF OSWEGO, NEW YORK.

ELLIPTIC SPRING.

SPECIFICATION forming part of Letters Patent No. 718,784, dated January 20, 1903.

Application filed July 29, 1901. Serial No. 70,040. (No model.)

To all whom it may concern:

Be it known that I, THOMAS ALEXANDER SHEA, of Oswego, in the county of Oswego, in the State of New York, have invented new and useful Improvements in Elliptic Springs, of which the following, taken in connection with the accompanying drawings, is a full, clear, and exact description.

My invention relates to elliptic springs; and it consists in providing an end plate or end connection arranged between the upper and lower halves of the spring, forming a convenient mode of connection, so that the springs are easily assembled and disassembled, the weakening of the main plates adjacent to their points of connection is overcome, and the risk of breaking lessened. Heretofore the upper and lower halves of elliptic springs have commonly been formed with scrolls or eyes at their ends connected by a pin with a curve or neck in the main leaves adjacent to the scroll. This neck was a weak point, and the main leaf could not there be reinforced, because if the second leaf or leaves were elongated for that purpose they would slide on the main leaf when used and strike the projecting eye. In my spring the ends of the halves are connected by these peculiar end plates, which retain the springs in proper relative position, their center and side flanges confine the ends in alignment, preventing them from twisting out of true, and the plates themselves move easily as the springs are elongated or contracted by changes in load and afford a bed for the ends of the halves. With no load or with light load the weight is supported on the extreme ends of the springs, promoting easy running, and as the load increases the springs are compressed and shortened on the bed, thereby increasing the capacity and resistance in proportion to the load, meeting the present needs of heavy cars, locomotives, tenders, &c., supported on large elliptic springs. The spring must be adapted to support a heavy load; but when the car is light it must be adapted to give easy running, that the car may not shake and rattle itself.

My invention will be understood by reference to the accompanying drawings, in which

the reference-numerals of the specification indicate the same parts in all the figures.

Figure I is a side elevation of an elliptic spring provided with my end connections, of which one is shown in section. Fig. II is a top plan view of a double-elliptic spring so supported. Fig. III is an isometric view of one of my peculiar end plates. Fig. IV shows an end plate for a triplicate spring.

In the figures, 1 1 indicate the main leaves, 2 2 the second leaves, and 3 3 the shorter leaves, of elliptic springs held in position by the band 4. My peculiar end plates or end connections (indicated by 5) are similarly formed above and below with beds 6 6, arranged between the center flange 7 and the respective side flange 8, receiving and supporting the end of the semi-elliptic—that is, the end of the main—leaf, which is drilled at 9 to fit studs 10 10, by which the end plates are held in position between the halves of the spring. These studs may be hollowed in their ends to diminish the weight and amount of stock, and for the same purpose the center flange may be channeled and the outer flanges curved or beveled on their outer edges. My end plates are adapted for the connection of the halves of any number of elliptic springs—double elliptics, as shown in Figs. I, II, and III, and a triplicate, as shown in Fig. IV. These end connections are economical and simple to cast or otherwise construct from steel or iron and adapted to be used with elliptic springs for supporting the heaviest loads. Malleable iron is a suitable material. The second leaves 2 2 may be elongated, as shown in the figures, adjacent to the studs to reinforce the main leaves, entirely doing away with the weak point or neck of the prior scroll elliptics. If for any reason a leaf breaks, it is easy to take the springs apart and substitute a new leaf, whereas in the old scroll-spring a special machine was necessary to make the scroll. Therefore it was easier and cheaper in case of a break to throw away the whole spring.

The operation of the spring under light and heavy load is indicated in Fig. I. The full lines show the weight supported on the extreme ends of the main leaf with the light

load, giving easy running. The dotted lines show the result with heavy load, when the springs shorten on the bed, giving greater capacity.

5 Having thus described my invention, what I claim, and desire to secure by Letters Patent, is—

1. In an elliptic spring, the combination with the upper and lower halves, of end plates

10 arranged near the ends of said halves at each end, said end plates being formed above and below with beds on which bear the ends of the main leaves, with integral side flanges extending above and below on each side of said leaves, and with integral studs fitting perforations adjacent to the ends of the main leaves.

2. In combination with a series of elliptic springs, of end plates arranged between the ends of the upper series and of the lower series of longitudinal, bearing-beds, the respective beds being of sufficient width to receive freely the ends of the springs, of integral side flanges extending above and below on the ends of the end plates adjacent to the outer edges of the main leaves, of integral center flanges extending above and below between the adjacent edges of the main leaves, and of integral studs extending above and below adjacent to the outer edges of the end plates 30 adapted to fit corresponding perforations in the ends of the main leaves.

3. In an elliptic spring, the combination of upper and lower halves composed each of a main leaf and a series of superimposed leaves, 35 of end plates arranged between the ends of the main leaves, said plates being formed with beds above and below to receive the ends of the main leaves, with studs near their outer edges extending above and below fitting perforations adjacent to the ends of the main leaves, the second leaf of each half being extended adjacent to the stud to reinforce the same.

4. In an elliptic spring, the combination of upper and lower halves composed of a main leaf and a series of superimposed leaves, of end plates arranged between the ends of the main leaves, said plates being formed with beds above and below to receive the ends of the main leaves, with studs near their outer edges extending above and below fitting perforations adjacent to the ends of the main leaves, and with integral flanges extending above and below and on each side of each leaf, the second leaf of each half being extended adjacent to the studs to reinforce the spring.

5. In an elliptic spring, the combination with the upper and lower halves, of end plates interposed between the ends of said halves, and formed above and below with beds to receive the ends of the main leaves, and with projections to engage with openings in said leaves.

6. In an elliptic spring, the combination with the upper and lower halves, of the main leaves thereof having substantially straight ends, end plates arranged between the ends of the leaves, and formed with bearing-beds above and below for said main leaves, and 70 with integral, longitudinal, parallel flanges to confine the ends of said leaves, and engaging means between the end plates and the main leaves whereby they are connected.

7. As a new article of manufacture, an end plate for elliptic springs having longitudinal bearing-beds for the ends of the halves of the spring, integral, longitudinal flanges on each side of each bed, and integral studs projecting from each bed.

In testimony whereof I have hereunto signed my name.

THOMAS ALEXANDER SHEA.
